UNITED STATES PATENT OFFICE.

CHESTER M. MACCHESNEY, OF CHICAGO, ILLINOIS, ASSIGNOR TO ACME STEEL COMPANY, OF CHICAGO, ILLINOIS, A CORPORATION OF ILLINOIS.

STRAPPING APPARATUS.

Application filed August 8, 1921. Serial No. 490,478.

The present invention has been primarily directed toward obviating certain difficulties encountered in the bundling of wall paper. Wall paper is ordinarily put up in bundles of generally cylindrical form and the process consists in laying a predetermined number of rolls of paper in the trough of a buck, with or without a sheet or strips of wrapping material, and tying up the bundle with string or cord generally at two places a short distance from the ends of the bundle. Ordinarily the paper is still hot when put up in these bundles and the result oftentimes is that shrinkage coupled with stretchiness of the string or cord causes the bundle to loosen up and fall apart. My invention relates to the use of steel strapping instead of string or cord, i. e., such strapping as is extensively used upon boxes, bales, and various kinds of packages and which has all the stretch taken out of it when put in use. I have found that this steel strapping can be applied under very considerable tension to a bundle of wall paper rolls without any injurious effect whatever while at the same time the bundle will continue to be held tight notwithstanding it may shrink considerably. In carrying out my invention I provide for simultaneously stretching two lengths of the strapping applied at two different places around the bundle at short distances from its ends, employing mechanical appliances for this purpose. It is quite necessary to have the strapping under considerable tension around the bundle and it would be impracticable to first apply strapping near one end of the bundle and then apply it near the other end, for the result would be that in the first application of the strapping there would be a spreading and bulging at the unconfined end, and then if strapping was afterwards applied at that end a symmetrical bundle could not be formed, besides which the considerably expanded end of the bundle would be awkward to strap and the smoothness of the rolls of wall paper would be disturbed in the compacting of the bundle and it would be difficult if not impossible to keep the outside wrapping at all smooth.

I have devised a special form of buck for retaining the wall paper rolls to make up a bundle and my complete strapping apparatus as here illustrated and presently to be described in detail embraces reels from which

strapping can be drawn to be laid around the bundle in the buck at two places near its ends, and a stand between which and the reels the buck will be located, said stand carrying a pair of strap-stretching tools so mounted as to provide for their being simultaneously lowered upon the bundle and simultaneously operated to stretch the two lengths of strapping.

In the drawings which accompany and form part of this specification Fig. 1 shows the complete apparatus in side elevation ready to be operated; Fig. 2 is a similar illustration showing the condition during the operation of stretching the strapping around the bundle; Fig. 3 is a top plan view of the apparatus; Fig. 4 is a top plan view of the stretching tools and their mounting; and Fig. 5 is a detail sectional view taken substantially on the line 5—5 of Fig. 4.

Referring first to the buck, this is composed of a simple framework on swivel casters, the uprights of which are designated 2, and in its upper part it has a trough made out of sheet metal 3. This sheet of metal is flanged and securely nailed to the top of the frame at one side as indicated at 4. It is sufficiently free otherwise to provide for expansion and contraction of the trough to regulate the size of the bundle. This sheet of metal is curved in generally cylindrical form and is free from attachment to the frame as it extends down into the same and around and up to the back part thereof, so that it may expand or contract to suit varying sizes of bundles. Slotted brackets 5 on the back upper part of the sheet metal trough and extending alongside the rear uprights of the buck frame provide for fixing the trough at different adjustments as to size of the bundle, the said slotted brackets receiving screw studs which project from said uprights and have clamping nuts 6 applied to them.

Referring next to the strap stretching part of the apparatus, an upright stand 7 is secured to the floor where the portable buck can conveniently be rolled into position immediately behind it, the height of this stand being approximately that of the buck. Between the uprights of this fixed stand at the top there extends a pivot rod 8 and on this rod are journaled two blocks 9 spaced apart and rigidly connected by a bar 10. There is mounted upon each block a stretching tool

100

105

110

- the base 11 thereof resting squarely upon the top of the block and having tapped into it a bolt 11* which extends through the block from the underside as clearly illustrated in 5 Fig. 5. The stretching tool here shown is of substantially the same construction as that disclosed in the application filed July 14, 1920, Serial No. 396,309 by myself jointly with Ralph H. Norton, said tool having been 10 specially designed for use upon round packages. The base 11 of the tool has a rack cut in its upper side and a slide 12 embraces the base bar and carries a gear wheel 13 in mesh with the rack and adapted to be 15 ratcheted in one direction by a pawl carried in an operating hand lever 14. The slide has a gripping couple 15 at one side and in line with a similar couple 16 carried by a laterally projecting portion of the base bar 20 at the outer end thereof. The base bar of each of the tools at the opposite ends is extended somewhat beyond the blocks 9 and the two extended portions of the base bars are connected together by a cross-bar 17. 25 This cross-bar is pivotally connected with the tool base bars so as to provide for lateral shift of the latter as indicated by dotted lines in Fig. 4, and the purpose of which will be presently pointed out. A handle 18 30 on the cross-bar 17 provides a ready means for swinging the two tools up and down and for laterally shifting them. A spring 19 connects the said cross-bar with a lower portion of the stand 7 and serves as a counter- 35 balancing means for keeping the tools elevated when they are not in use. Another spring 20 extends horizontally between said cross-bar and a portion of the stand for the purpose of normally holding the tools and 40 the block structure 9—10 over against one side of the stand, it being understood that the blocks 9 are slideable on the pivot rod 8, said spring also serving to normally hold the tools at right angles to the block structure. 45 A bracket 21 secured to the cross-bar 10 of the block structure limits the swivel movement of the tools in the direction in which the said spring 20 pulls and also limits their movement in the opposite direction. 50 In rear of the stand 7 with space between to accommodate the buck, there is another stand 22 which carries a pair of strapping reels 23 spaced apart the same distance that the strapping is to be spaced on the bundle. 55 In operation the buck is rolled in between the stands 7 and 22 and brought to position just in rear of the stand 7 and with those portions of the bundle where the strapping is to be applied in line with the said reels. 60 A piece of wrapping paper will have been laid smoothly in the trough of the buck and the proper number of rolls of wall paper to make up a bundle will have been laid in over the wrapping paper in orderly fashion 65 and then with the buck in its proper position just in rear of the stand 7 the operator will lay down the wrapping paper over the top of the bundle, draw a supply of strapping 24 from one of the reels and take it under the bundle where it projects beyond the trough 70 at one side, thread a sealing sleeve over the strapping and bend the end of the latter and hook it over the under member of the gripping couple 16 of one of the tools. Then the strapping will be laid over the bundle 75 from the rear and slipped between the members of said gripping couple overlying the hooked end of the strapping and also slipped between the members of the other gripping couple 15. The strapping will be pulled up 80 to take out slack and then the gripping couple 15 will be closed tightly upon it. The same procedure will be gone through with at the other end of the bundle, both tools having previously been lowered upon 85 the bundle as illustrated in Fig. 2. Thereupon the operator will work both tool handles 14 to simultaneously stretch the strapping around the bundle. When this has been done to the requisite extent the 90 gripping couples 16 will be tightened upon the strapping and the latter will be released from the gripping couples 15 and cut off. The sealing sleeves which were threaded upon the strapping at the beginning will 95 then be slipped over the cut off ends of the strapping and a sealing tool will then be applied for interlocking the overlapped ends of the strapping and interlocking them with the sealing sleeves. Reference may be had to the Norton and Fork Patent No. 1,322,723 100 with respect to such interlocking by the application of the tool in question. 105 Each of the bases of the stretching tool, besides having the lateral extension or arm at its outer end carrying the gripping couple 16, has a similarly extending projection or arm 25 sufficiently spaced away from the said gripping couple to provide for the introduction of the sealing tool. The space between the said arm 25 and the said gripping couple is closed over its bottom by a plate 26 on which the said sealing tool may 110 rest while it operates upon the overlapping portions of the strapping extending across 115 the space and embraced by the seal. 115 When the operations just previously described have been performed shouldered portions of the lateral arms 25 of the stretcher tools will be under the stretched strapping 120 between it and the bundle, and likewise shouldered portions of the lower members of the gripping couples 16 will be under the strapping. Now the mounting of the two stretcher tools upon a slide (9—10) to which they are swiveled is for the purpose of providing a ready means of disengaging the tools from the strapping with dispatch. To accomplish this the operator takes hold of 125 the handle 18 and gives it a quick, short 130

throw leftward, the gripping couples 16 having meantime been released. The engagement of the shouldered lower members of said couples with the side edges of the strapping will produce a fulcruming effect, the blocks 9 sliding along the rod 8 while the tools turn upon their swivel connections with said blocks and the jointed connection between the rear ends of the tools accommodating itself to the movement. The result of this is to take the arms 25 from under the strapping which will immediately snap down across the ends of these arms. Thereupon there is a reverse action (effected either by the operator throwing the handle 18 back to the right or by his simply permitting the spring 20 to do the work) and now the fulcruming effect is had between the side edges of the strapping and the ends of the said arms 25, with the result that the lower members of the gripping couples 16 are taken from under the strapping. This frees the tools entirely from the strapping and the operator, pressing down upon the handle 18 or upon the bar 17, throws the tools up and the buck containing the strapped bundle is rolled away and another put in its place.

In order to insure correct positioning of the buck fore-and-aft between the reel stand 22 and the tool stand 7 so as to secure the most advantageous relationship between the tools and the bundle, I employ a gauge for the buck to abut. This gauge is in the form of a yoke whose cross-bar 27 presents the abutment for the buck and whose side arms are slotted and extend along the uprights 7 of the tool stand receiving clamping bolts. The latter are designated by the numeral 28 and have nuts applied to them, and the purpose of this adjustment is to provide for varying the positioning of the buck to suit different sizes of bundles. If the bundles vary to any considerable extent in diameter some change in the fore-and-aft position of the buck will be desirable in order that the tools may take up the most advantageous position on the bundle when the strapping

operations are to be performed. It is desirable in the interest of ensuring tightness of the strapping that the end portions of the tools do not project past their points of contact with the bundle so as to overhang and therefore require the strapping to extend away from the bundle an appreciable amount in passing to the gripping couples 16. Therefore, in case of strapping a bundle of much smaller diameter than the one illustrated, the gauge 27 would be set further out from the stand 7. On the other hand, if the buck was designed to hold a much larger bundle than the one shown, the gauge would be set further in, since it is likewise desirable to avoid having those portions of the tools where the arms 25 are located project away from the bundle.

I claim:

1. Strapping apparatus comprising a plurality of stretching tools, and a laterally shiftable mounting therefor on which the tools are swiveled, said mounting being pivoted to provide for vertical swing of the tools.

2. Strapping apparatus comprising a stand, a pivot rod in the upper part of the same, a slide pivotally mounted thereon, and a plurality of stretching tools tied together through pivoted connections and swiveled on said slide.

3. A bundling buck comprising a frame and a flexible trough with provisions for expanding or contracting the same for different sized bundles.

4. A bundling buck comprising a frame, a flexible trough fixed at one side to the frame, and adjustable clamping means at the other side between the trough and the frame to provide for different sized bundles.

5. A bundling buck comprising a frame, a flexible trough fixed at one side to the frame, and slotted brackets and screw clamps at the opposite side between the frame and the trough to provide for different sized bundles.

CHESTER M. MACCHESNEY.
